[57] CLAIM

The ornamental design for a hair curl protector, as shown and described.

DESCRIPTION

FIG. 1 is a perspective view of a hair curl protector, showing my new design;

FIG. 2 is a side-elevational view of the side not seen in FIG. 1;

FIG. 3 is an end-elevational view thereof; and

FIG. 4 is a bottom-plan view thereof.

FIG. 1

FIG. 2

FIG. 4
